ARTIFICIAL LIMB

Charles H. Davies, Philadelphia, Pa.

Application May 4, 1935, Serial No. 19,897

5 Claims. (CL. 3-2)

The present invention relates to improvements in the knee and ankle joint structure of artificial limbs, whereby their reliability is enhanced and a controlled knee action provided. Since the invention will be best understood from a detailed description of a specific exemplification, such a description will be given with reference to the accompanying drawings which show a practical embodiment.

10 In the drawings:

Figure 1 is a side elevation of an artificial limb embodying the present invention.

Figure 2 is a vertical section of the limb of Figure 1.

15 Figure 3 is a section substantially on line 3-3 of Figure 1.

Figure 4 is a rear elevation of the knee joint of Figure 1.

20 Figure 5 is a front elevation of a bracket utilized in the knee joint.

Figure 6 is a section substantially on line 6-6 of Figure 1.

Figure 7 is a bottom plan view of the lower end of the shin section, and

25 Figure 8 is a plan view of the heel portion of the foot.

Referring to the drawings, reference numeral 10 designates the thigh portion of an artificial limb, reference numeral 11 the shin portion, and 30 reference numeral 12 the foot portion. The thigh and shin portions are of hollow, preferably metal, construction, the spun and formed thigh section having a closed lower end as here shown, Figures 2 and 3.

35 The top edge of the shin portion is substantially flat as to its forward portions as at 13, Figure 3, its rear portion dropping substantially as at 14. The upper margins of the shin portion are circumferentially rimmed inwardly by

40 a welded bracket 15, the bracket being preferably an integral unit and comprising a forward band 16 and a rearward downwardly extending band 17 whose top edges are flush with edges 13 and 14 respectively. Intermediate edges 13 and 14 the

45 shin is provided with arcuate recesses 18 and 19 and bands 16 and 17 have at their junctures upstanding ears 20 and 21 outwardly enlarged to provide bosses which are received in recesses 18 and 19. The outer faces of the bosses are substantially flush with the outer surfaces of the shin portion and will substantially merge with the latter during the welding operation so that a flush exterior is provided.

50 Ears 20 and 21 are provided with hexagonal apertures which taper toward the right, Figure 3.

the aperture in ear 20 being larger than that in ear 21. These apertures receive the tapered hexagonal throat and tip portions 23 and 24 of a round bolt 25 which is relieved medially to provide a hexagonal section 26. Bolt 25 has a head 5 27, and its tip is provided with a tapped bore in which is threaded a retaining screw 28. The original clearances are such, with the hexagonal portions of the bolt wedged in the receiving apertures, that upon the occurrence of wear the bolt 10 may be axially displaced by tightening screw 28 to re-engage it tightly in the apertures. Due to the non-round shape of the apertures, bolt 25 is rigidly held against rotation relative to the shin portion.

15 The side walls of the lower end of the thigh portion 10 are inwardly bulged and apertured to receive nipples 29 and 30 which have outer end flanges received in the inwardly offset margins of the apertures and abutting the same. The 20 apertures are rimmed by inwardly projecting annular flanges, Figure 3, to provide ample bearing surfaces for the nipples. The inwardly extending externally threaded portions of the nipples have screwed thereon retaining rings 31 and 32, which are engaged around the annular flanges and have dished radial flanges engaging around the annular shoulders provided by the bulged side walls, the margins of the side wall apertures being clamped between the nipples and rings.

30 Nipple 29 has an integral annular flange 33 against which abuts an inner ball race 34, the outer race 35 being threaded in the outer end of nipple 29. Nipple 30 has a similar flange 36 and carries the inner and outer races 37 and 38. 35 The inner races 34 and 37 bear on pivot bolt 25. Non-metallic washers are preferably interposed between the ball bearing assemblies and the bearing ears 20 and 21.

30 The outer portions of the bearing carriers 28 and 38 are substantially flush with the side walls 40 of the thigh portion and are retained securely in position not only through engagement with the annular flanges of the side wall apertures and the friction of the clamping members, but also 45 through the positive abutment provided by the cupped-flanges of the rings 31 and 32. The carriers are thus most rigidly secured in position.

Clamped on the hexagonal portion 26 of pivot bolt 25 is a split brake drum comprising the two 50 parts 39 and 40. The part 39 is provided with a notch, shaped to fit against three sides of the hexagon 26, the two opposite sides of the notch being continued outwardly to the split which is in a plane remote from the bolt axis. The drum 55

- portion 40 has lug portions 41 and 42 projecting into the notch of portion 39 and engaging the other three sides of the hexagon 26. The drum parts are clamped securely against the pivot bolt 5 by means of screws 43 and 44 whose heads are inset in part 40 below the periphery thereof. A pair of arms 45 and 46, here shown as integral with part 39, project substantially radially from the latter and at their outer ends carry a roller 10 47 under which is passed, between the arms, a control strap or suspender 48. Arms 45 and 46 constitute a knee lever of which drum 39, 40 is in effect the hub. Strap 48 is passed out through openings in the thigh portion 10 in the 15 well known manner and may have its ends secured to a belt, the top forward portion of the strap being constituted by an elastic band.
- A band 49 has one end bolted or riveted to the rear wall of the thigh portion and is looped around 20 hub 39, 40 between the lever arms. The other end of the band has secured thereto a threaded stem 50 which is passed through an opening in the rear wall of the thigh portion to receive a wing nut 51. Band 49 has a friction liner 52 25 engaging the drum.
- By suitably adjusting nut 51 the band tension may be altered to modify the knee action as desired by the wearer, a principal purpose of the braking arrangement being to control the forward 30 movement of the shin portion, abrupt movement being prevented so that a more natural action is afforded.
- The knee action may also be readily modified by changing the angular position of the knee lever 35 and this may be accomplished without removing the pivot bolt by merely loosening screws 43 and 44, the top portion of the brake band being temporarily pulled in out of the way, and swinging the lever relative to the pivot bolt. The 40 screws have their major portions threaded into the drum portion 39 and may be threaded out sufficiently to permit swinging of the lever without their entire removal. Since the heads of the screws are faced upwardly, they are accessible 45 from the top of the thigh portion. Adjustment of the knee lever may, of course, also be effected by withdrawing the pivot bolt 25 sufficiently to enable it to be turned in its receiving apertures and then re-inserting it in a new position.
- The lower rear extremity of the thigh portion 50 is inwardly off-set at 53 and in the off-set is fixed a pad 54 of compressible material, the off-set and pad extending substantially from side to side of the thigh portion. Pad 54 is positioned to cooperate as an abutment with the 55 rear band 17 of bracket 15 substantially throughout the rear portion of the latter to limit forward movement of the shin portion relative to the thigh portion. Due to this elongated contact zone 60 even severe abutment shocks have no distortive effect on either of the limb portions, any such effect on the shin portion being prevented in the first instance by the intervention of the relatively rigid band 17 of the bracket. The bracket 65 15 thus not only serves to finish and reinforce the upper edge of the shin portion and to carry the pivot bolt, but it also serves as an abutment member to limit relative movement of the limb portions. It provides an extremely rigid top 70 structure for the shin portion and serves to distribute thrust thereto. Bolt 25, by reason of its hexagonal end portions engaged in mating openings in the bracket, is securely held against rotation relative to the shin portion and this is of 75 great importance inasmuch as the action of the

suspender and also of the brake is transmitted through this bolt. This rigid construction is completed by the secured clamping of the lever and drum to the hexagonal medial portion of the bolt. The bracket 15 is preferably an aluminum forging for the sake of lightness and strength.

The rear of the thigh portion at the knee is flattened as indicated at 55 and upwardly curvilinearly merged into a curved junction line 56 with the surmounting wall portion. The line 56 is so chosen that upon extreme relative bending of the limb portions it will abut substantially throughout, the rear reinforced edge of the shin portion. Due to this elongated zone of contact and also due to the thickened upper rear edge of the shin portion, local crushing effects on the rear wall of the thigh portion are avoided. As may be seen from Figure 2 when the thigh portion has been bent relative to the shin portion to bring about abutment between the upper edge 20 of band portion 17 and the thigh portion at 56, the latter has moved through an angle substantially greater than a right angle relative to the shin portion. This is important as enabling the wearer to kneel without a tendency to be 25 thrown forwardly off balance.

The lower edges of the shin member are in substantially the same plane except that each side wall has an arcuate downward extension, these being designated as 57 and 58. In the heel portion is set an inverted cup-like member 59 which has side and rear flanges welded to the walls of the shin portion. Member 59 is to the rear of the extensions 57 and 58. A plate 60 is welded to the front lower edges of the shin portion, and a heavier plate 61 underlies the lower forward edges of the shin portion and is secured to plate 60.

The ears 57 and 58 are inwardly off-set as are also the side wall portions thereabove, depressions 62 and 63 being thus formed. The ears have outwardly projecting flanges, Figures 6 and 7, which form lower bounding walls for the depressions. Each of the depressions has frontwardly and rearwardly extending branches as at 62a and 62b, Figure 1, and inserts 64 and 65 are received in the respective recesses, each being shaped as shown in Figure 1. In this figure the insert 64 is shown, the insert having arms 64a and 64b extending into the branches 62a and 62b, the lower portions of the inserts overlying ears 57 and 58 and abutting the flanges of the latter. The inserts are welded in position and carry in suitable openings ball bearing assemblies 66 and 67 which may be screwed or pressed into position, the inner races receiving the reduced ends of a pivot bolt 68 into the ends of which are threaded screws 69 and 70 which engage washers overlying the outer ends of the inner races of the ball bearing assemblies. The latter are assembled with the inserts after the ends of bolts 68 have been positioned in the 60 insert openings.

While I have stated that inserts 64 and 65 are welded in place, it will be understood that this is the practice preferred by me and that rivetting or other suitable assembly practice may be used if desired. The same, of course, applies to bracket 15 and other parts.

The central portion of bolt 68 is engaged in the eye of a bolt 71 whose threaded stem is passed through the foot and engaged by a nut 72. The foot supports a bolster 73 which has two channel portions 74 and 75 of arcuate cross section, in which the end portions of bolt 68 are seated, a non-metallic cushion 76 being interposed between

the bolt and the channel portions. Bolt 71 extends through the slot 77 which separates the channel portions 74 and 75. The latter have fixed in their bottom walls upwardly projecting pins 78 and 79 which engage with a close fit in sockets in the underside of the pivot bolt so that the latter is securely held against rotation and axial displacement. Bolt 71 is secured to bolt 68 through a set screw 80, but since this screw may come loose and since moreover the stem may wear away and enlarge the bore in the foot through which it is passed, I have provided the pin and socket connection which insures that the pivot bolt will be held absolutely fixed, the cradle, it will be understood, being rigidly fixed in the foot portion. The ankle connection is completed by an elongated rubber pedestal 81 interposed between the heel of the foot and the shin portion with its upper end seating in cup 59 and a rubber pad 82 interposed between the foot portion and plate 61. The described ankle assembly is very resistant to torsional stresses, the lower end of the shin portion being reinforced in this respect by the frontwardly and rearwardly extending arms of the inserts.

It will be observed that the bracket 15 positions the pivot bolt 25 nearer the rearward than the forward portion of the upper edge of the shin portion and that the pivoting axis of the thigh portion is similarly rearwardly positioned. This is important in that with this relation of parts the weight of the wearer is predominantly forward of the pivoting axis in the straightened relation of the limb portions so that the lower rear surface of the thigh portion tends to maintain its abutting relation with the rear band portion 17. Accidental bucking forward of the knee is thus prevented.

Since changes in form and arrangement may be made from what has been described without departure from the scope of the invention, it will be understood that I do not limit myself in these respects except as in the following claims.

I claim:

1. An artificial limb comprising a thigh portion and a shin portion articulated by means of a pivot bolt which is non-rotatable relative to the shin portion, a split brake drum fixed on said bolt, means fixed to the thigh portion and frictionally engaging said drum, and a lever for engagement by a control strap, said lever being formed with and projecting radially from one of the parts of said split drum.

2. An artificial limb comprising a thigh portion and a shin portion articulated by means of a pivot bolt which is non-rotatable relative to the shin portion, a brake drum fixed on said bolt, a brake band anchored in said thigh portion and operatively engaging said drum, and a lever for engagement by a control strap, said lever being secured to said drum, the lever having parallel arms projecting substantially radially from said drum, the brake band being guided between the lever arms.

3. An artificial limb comprising a hollow shin portion and a bracket including a band portion secured to the upper margins of said shin portion throughout the circumferential extent of the latter, said bracket having integral bearing portions for a pivot bolt, a pivot bolt supported in said bearing portions, a thigh portion pivoted on

said bolt, the rear part of the band portion being downwardly off-set relative to its forward portion and having a downwardly curved upper edge adapted to abut the rear surface of the thigh portion to limit relative bending in one direction of the two limb portions, said rear surface being transversely curved and the curve of said upper edge conforming substantially thereto to provide extended abutting contact, said thigh portion having a lower rear part extending in front of and abutting the rear part of said band portion when the two limb portions are in straightened relation.

4. An artificial leg comprising a thigh portion, a hollow shin portion having a downwardly curved upper edge at its rear, a bracket secured to the shin portion and comprising a pair of spaced bearing portions adapted to receive a pivot bolt and a band portion joining said bearing portions, said band portion extending across the rear of said shin portion adjacent the upper edge of the shin portion and being arched downwardly between the bearing portions and conforming substantially to the curvature of the upper edge of the shin portion adjacent the same, the thigh portion having at its lower end a rear wall extended downwardly below said bearing portions sufficiently to engage the front surface of said band portion when the thigh and shin portions are straightened whereby the band portion serves as a combined reinforce for the shin portion and as a stop for limiting relative movement between the same and the thigh portion, the downward arching of the band portion permitting the thigh portion to move through an angle greater than a right angle to the shin portion, the top of said band portion serving as a stop for limiting such angular movement.

5. An artificial leg comprising a thigh portion, a hollow shin portion having a downwardly curved upper edge at its rear, a bracket secured to the shin portion at its upper end and comprising a pair of spaced bearing portions positioned at the sides of said shin portion and a forwardly extending curved band portion joining said bearing portions and secured along the forward edge of said shin portion, a rearward band portion joining said bearing portions and secured along the upper edge of said shin portion at its rear, said band and bearing portions being integral, the rearwardly extending band portion being arched downwardly between the bearing portions whereby to conform substantially to the curvature of the upper edge of the shin portion, the thigh portion having at its lower end a rear wall extended downwardly below said bearing portions sufficiently to engage the front surface of said rearward band portion when the thigh and shin portions are straightened whereby the band portions serve as a combined reinforce for the shin portion and the rearward band portion serves as a stop for limiting straightening movement of the shin and thigh portions, the downward arching of the rearward band portion permitting the thigh portion to move through an angle greater than a right angle relative to the shin portion, the top of said rearward band portion serving as a stop for limiting such angular movement.
